UNITED STATES PATENT OFFICE.

WILLIAM EVERETT QUIMBY, OF ORANGE, NEW JERSEY.

DESIGN FOR A SCREW.

SPECIFICATION forming part of Design No. 23,336, dated June 5, 1894.
Application filed January 19, 1894. Serial No. 497,444. Term of patent 14 years.

To all whom it may concern:

Be it known that I, WILLIAM EVERETT QUIMBY, of Orange, Essex county, New Jersey, have invented and produced a new and original Design for a Screw, of which the following is a specification.

Figure 1 is an elevation of a screw showing my design. Fig. 2 is a section thereof.

Similar letters of reference indicate like parts.

My design consists in the configuration of the screw as hereinafter described. The thread A has the appearance of being wound spirally about the cylinder B. The width of the periphery of said thread, as from a to b, is equal to the interval c d on the cylinder between successive turns. In each of the side walls of the thread appears a recess which is so curved at the bottom that upon a

radial line it gradually increases in depth, as at C, from the periphery of the thread to a point near the base, and from that point, as shown at D, rapidly diminishes in depth to the base. The resulting configuration of each of the thread walls upon any radial line, that is, a line extending from any point on the periphery to the center of the core, or cylinder, of the screw is therefore that of a somewhat irregular curve, substantially as shown.

I claim—

The design for a screw substantially as herein shown and described.

WILLIAM EVERETT QUIMBY.
